UNITED STATES PATENT OFFICE.

HENRY A. WEIHMAN, OF PHILADELPHIA, PENNSYLVANIA, ASSIGNOR TO
SIMONS, BROTHER & CO., OF SAME PLACE.

DESIGN FOR A CANE OR UMBRELLA HANDLE.

SPECIFICATION forming part of Design No. 19,972, dated July 1, 1890.

Application filed April 15, 1890. Serial No. 348,091. Term of patent 3½ years.

To all whom it may concern:

Be it known that I, HENRY A. WEIHMAN, a citizen of the United States, residing in Philadelphia, in the county of Philadelphia and State of Pennsylvania, have invented and produced a new and original Design for Cane or Umbrella Handles, of which the following is a specification, reference being had to the accompanying drawings, forming part thereof.

10 In the drawings, Figure 1 is a side elevation of a cane or umbrella handle embodying my new design; and Fig. 2 is a similar view of the same, but looking from another direction.

A is the body part, and is slightly convex, being somewhat larger at the top than at the bottom, and is formed with a series of spiral grooves D, ornamented at intervals with the ornamentation-work E F F. The head B of the body part is made slightly curved and 20 plain.

C is the base portion, and is separated from

the body part by an annular band G. This body portion is ornamented by a series of downwardly-projecting points H of plain surface, with a groundwork I of ornamental or 25 shaded work, and the whole is finished by a second annular band J, of the same or larger diameter than the band G.

The handle is made of any suitable material.

Having now described my new design, what I claim as new, and desire to secure by Letters Patent, is—

The design for an umbrella or cane handle, substantially as herein described and shown. 35

In testimony of which invention I have hereunto set my hand.

HENRY A. WEIHMAN.
